UNITED STATES PATENT OFFICE.

THOMAS LE ROY PARKER, OF CHICAGO, ILLINOIS.

SNAP-SWITCH.

1,163,685.

Specification of Letters Patent. Patented Dec. 14, 1915.

Application filed October 19, 1914. Serial No. 867,442.

To all whom it may concern:

Be it known that I, THOMAS LE ROY PARKER, citizen of the United States of America, residing at Chicago, in the county of Cook and State of Illinois, have invented certain new and useful Improvements in Snap-Switches, of which the following is a description.

My invention belongs to that general class 10 of devices commonly termed snap switches, which are so constructed that electrical connection is made in light systems by the turning of a shaft or post, the parts being so constructed that the electrical connection 15 will be maintained complete until at the instant the parts are quickly separated with a snap, thus reducing the liability of burning out the parts by incomplete connections.

My invention has for its object the construction of such a device in a simple and effective manner, at a reasonable cost.

To this end my invention consists in the novel construction, arrangement and combination of parts herein shown and described, and more particularly pointed out in the claims.

In the drawings, wherein like reference characters indicate like or corresponding parts, Figure 1 is a front elevation of my 30 improved device with the front cover plate partly broken away to illustrate the construction of the dial plate; Fig. 2 is a sectional view taken substantially on line 2, 2 of Fig. 3; Fig. 3 is a sectional view taken 35 substantially on the line 3, 3 of Fig. 2; Fig. 4 is a fragmentary sectional view taken substantially on line 4, 4 of Fig. 3, and looking to the left, as indicated in the arrows nearest to the device; Fig. 5 is a view taken substantially on the same section, which for identification we have marked 5, 5 on the Fig. 3, but looking in the opposite direction, that is to the right, as indicated by the arrows farthest from the device; Fig. 6 is 45 a partial longitudinal cross section substantially on the line 6, 6 of Fig. 2, showing certain parts in section and other parts in full lines; Fig. 7 is a view showing the various parts separated and indicating their 50 relative positions as the device is assembled, the shaft and the sleeve thereon being omitted to more clearly illustrate the construction; Fig. 8 is a perspective view of the device, the cover plate and dial being 55 broken away to more clearly illustrate the construction, and Fig. 9 is a section taken substantially on line 9, 9 of Fig. 6.

In the drawings, 1 indicates a base of suitable insulating material provided with a cover 2, through which extends the insulated thumb piece 3 secured to and controlling the rotation of the shaft. A guiding sleeve 4 is preferably positioned in the base, and maintained therein by the nut 5. The shaft 6 extends through the guiding sleeve, 60 as indicated in Fig. 3, the washer 7 secured thereon maintaining the parts in suitable operative position. A ratchet 8 is firmly embedded in the base, and preferably secured thereto by being threaded upon the 65 guiding sleeve 4, the projection 9, 9 embedded in the material of the base, serving to firmly hold the ratchet in position against movement. Superimposed or resting upon the ratchet is a sliding plate 10, having 70 formed therein a central opening constructed to coöperate with an eccentric cam hereafter described, and two or more guiding slots 11, together with a projecting finger or lug 12, formed to coöperate with the 75 teeth of the ratchet successively, as hereafter described. Superimposed upon the sliding plate 10 is a spider 13, loosely mounted on the shaft and provided with 80 lugs or extensions 14, positioned in the guiding slots 11, and thus insuring the lateral movement of the plate 10, as well as its rotation with the spider. Resting upon the spider and insulated therefrom by suitable 85 insulating washers 15, are switch blades 16 and 17, electrically insulated from each other by a suitable insulating material 18 positioned therebetween. Suitable retaining bolts 19 extending through the free arms 90 of the spider and the switch blades serve to 95 secure the parts firmly together, with the blades being suitably insulated from said bolts as stated. The free ends of the switch blades 20, 21 are arranged to closely embrace, and thus form electrical connection 100 with the stationary contacts 22, which are secured to the base, and are provided with suitable binding posts 23. Thus, as the shaft is rotated, the switch blades will alternately contact with the stationary contacts 22, and then be disengaged therefrom. 105 Suitable resilient connections between the shaft and the spider 13 are provided, so that as the shaft is rotated, the eccentric cam 24 positioned in the central opening of the slid- 110

ing plate 10, will move the plate along until the tooth 12 disengages the tooth of the ratchet 8 with which it is in contact. At this moment the resilient connection between 5 the shaft and the spider, and its connected parts will cause the latter to snap quickly forward until the tooth 12 engages the next tooth of the ratchet 8. There being four of such ratchet teeth, it will be seen that the 10 shaft will be given a quarter turn in each instance, alternately engaging the switch blades with the contacts, and disengaging them therefrom, the connection with and disengagement from the contacts being done 15 quickly and with a snap. For the purpose set forth a helical spring 25 embracing the shaft 6, may have its outer end connected directly to the shaft, if preferred, and its inner end connected to the spider 13. In the 20 preferred construction clearly shown in Figs. 3 and 6, a guiding sleeve 26 is positioned upon the shaft, the spring 25 loosely embracing the sleeve, and extending through the enlarged opening of the contact blades, 25 with the inner end of the spring engaging a stud on the spider, as shown in Fig. 9. The outer end of the device is preferably as follows: A sight opening 27 is formed in the cover 2; a dial 28 is secured to and 30 carried upon the shaft quartering the dial plate, are the words—"On"—and "Off"—alternately, so that as the shaft is turned the words will be alternately displayed through the sight opening 27. A washer 35 29 is firmly bent upon the reduced or flattened portion of the shaft 6 to engage the washer or collar therewith, the dial plate being preferably connected thereto, the outer end of the helical spring being hooked to 40 or engaged with a depending finger or projection 30 upon the washer. To insure the rotation of the dial 28 with the collar 29, I prefer to form an opening or slot 31 in the dial plate, in which a projecting finger 45 32 of the collar engages.

From the above description it will be seen that the purposes mentioned are obtained in the device described in a thoroughly practical and efficient manner. Most of the 50 metal parts being susceptible or being stamped out, insured an economical construction, securing at the same time great accuracy in the fitting and adjustment of the parts. In practical use I have formed the 55 plate 10 of stamped metal, the several openings and projecting stud 12 being formed at one operation.

Having thus described my invention, what I claim as new and desire to secure by Letters Patent is—

1. A snap switch, comprising a base pro-

vided with suitable contacts, and means for making wire connections therewith, a ratchet member operatively secured to the base, a coöperating sliding plate formed with a central opening and a wing having a guiding slot arranged therein, the said plate being provided with a second wing having a tooth arranged thereon adapted to successively engage the teeth in the ratchet, in combination with a rotatable shaft centrally maintained, an eccentric cam disk having a slot extending a part way therethrough fitted on the shaft, and operatively positioned in the central opening of the sliding plate, a rotatable spider loosely journaled on the shaft and disposed in parallel relation with the sliding plate having a projection on its under face located in the guide slot arranged in the outstanding ear of the sliding plate, switch blades carried by the spider and rigidly attached thereto adapted to co-operate with the contacts to make and break electrical connections therewith and a helical spring embracing the shaft with its outer end connected thereto, and its inner end bearing against the spider.

2. A snap switch comprising a suitable base provided with stationary contacts, and means for making wire connections therewith, a ratchet member operatively secured to the base, a coöperating sliding plate formed with a relatively large circular opening, and provided with diametrically opposite wing portions, one of said wing portions having a guiding slot therein, and the other wing portion having a projecting tooth thereon and a slot therein, the tooth adapted to successively engage the teeth of the ratchet, in combination with a rotatable cam 100 shaft centrally mounted, an eccentric disk secured to the shaft and operatively positioned in the central opening in the sliding plate, a rotatable spider on the shaft and disposed in parallel relation with the sliding plate having projections on the under face thereof located in the slots arranged within the ears of the sliding plates, switch blades rigidly secured to the sliding plate adapted to co-operate with the contacts to make and break electrical connection therewith, and a helical spring embracing the shaft with its outer end connected thereto and its inner end bearing against the spider.

In testimony whereof, I have hereunto signed my name in the presence of two subscribing witnesses.

THOMAS LE ROY PARKER.
